UNITED STATES PATENT OFFICE

NEAL G. BARNARD, OF MINNEAPOLIS, MINNESOTA

PENCIL SHARPENER

Application filed April 9, 1928. Serial No. 268,761.

My invention relates to a pencil sharpener of suitable size and shape to be conveniently carried in a pocket where it will be easily accessible at all times for use.

5 The object of the invention is to provide a simple, inexpensive holder for the sharpening blade adapted for the insertion of the pencil point therein and easily and conveniently manipulated by the thumb and fingers of one hand for tapering one end of the pencil and reducing it to the desired point.

10 A further object is to provide means for guiding the end of the pencil during the sharpening operation to the end that the degree of cut can be easily and accurately controlled.

15 A further object is to provide a simple, inexpensive means for securing the sharpening blade in the holder and in provision for an abrading surface to form a long tapered point on the pencil lead for the use of draftsmen and artists.

20 Other objects of the invention will appear from the following detailed description.

25 In the accompanying drawings forming part of this specification,

Figure 1 is a perspective view showing the pencil sharpener held in the hands of the user and illustrating the manner of seating the thumb of one hand against the holder and drawing the pencil across the sharpening blade with the fingers of the same hand;

30 Figure 2 illustrates the manner of holding the sharpening device while grinding or abrading the projecting lead of the pencil;

35 Figure 3 is a longitudinal sectional view showing the manner of guiding the pencil during the sharpening operation;

40 Figure 4 is a transverse sectional view on the line 4-4 of Figure 3;

Figure 5 is a perspective view of the sharpening blade; and

45 Figure 6 is a plan view of the blank or plate forming the shell or body of the sharpener.

In the drawing, 2 represents the middle portion of the blank and 3, wings or flanges folded in parallel relation at right angles substantially to the plate 2. This plate has a slot or opening 4 pressed or punched there-

from and a tongue 5 preferably integral with the plate at one end and projecting into the opening and spaced from the edges thereof, as indicated in Figure 6. This plate has a bend or shoulder 6 formed therein so that the end of the plate depends into the space between the wings 3 as indicated in Figure 3, a portion of the opening 4 separating the free end of the tongue 5 from the adjacent end edge of the opening. The plate 2 is also provided with a hole 7 and a tongue 8 that is bent upwardly and backwardly as indicated in Figure 3. A screw or other suitable means 9 fits within the hole 7 and into a blade 10 that is provided with a cutting edge 11 that is opposite and adjacent to the free end of the tongue 6. Whenever desired, this screw 9 may be loosened and the cutting blade removed for sharpening purposes or for repairs. The plate 2 and the wings thereon are 15 preferably formed of a suitable gage of metal that will be substantially rigid, and preferably the wings are provided adjacent their longitudinal edges with slots 12 pressed or punched therein. 13 is a plate having file 20 surfaces 14 and provided with lugs 15 which are adapted to enter the slots 12 and support the plate between the wings 3 in position where the user of the sharpener can at any time easily and conveniently apply the lead point of the pencil to the abrading surface of the plate and form a point of any desired length on the pencil. This feature of the device will commend itself particularly to artists and draftsmen, or to others requiring the use of pencils with long tapered lead points. The plate is set in from the edges of the wings so that the user can conveniently handle the device without smearing his fingers with the lead on the file surfaced plate.

25 The tongue 8 when bent to the position shown in Figure 3, forms a convenient thumb rest so that the user holding the device in one hand and the pencil to be sharpened in the other, can place the thumb against the rest and easily and conveniently draw the end of the pencil across the sharpening blade, and at the same time the yielding or resilient tongue 6 bearing on the end of the pencil will serve as a guide, and the degree of pressure applied 30

through the pencil to the guide will regulate the depth of cut of the sharpening blade.

Referring to the drawing, Figure 1 illustrates the usual method of holding the device in the hands during the operation of sharpening the pencil. The holder will be supported between the thumb and fingers of the left hand, with the thumb of the right hand seated against the tongue 8, the pencil being loosely held between the thumb and fingers of the same hand. The end of the pencil will then be engaged with the sharpening blade as illustrated in Figure 3, sufficient pressure being applied through the pencil upon the yielding tongue 5 to press the tongue outwardly and allow the cutting edge of the blade to form a shaving of the desired depth as the pencil is drawn across the cutting edge of the blade. The user can easily form the desired taper on the pencil by changing its angle with respect to the holder, and when the wood portion of the pencil has been suitably reduced, the desired point may easily and quickly be formed on the lead by rubbing it back and forth on the file surface of the plate beneath. This plate being set in a substantial distance from the edge of the holder there will be no opportunity for the fingers of the user being discolored by contact with the pencil point, or the accumulation of lead on the abrading surfaces of the plate. When not in use, the device is of such compact and convenient size it may be easily carried in the pocket.

The flap surfaces of the wings may if desired be used for advertising purposes. A suitable lettering or design may be impressed in the metal and suitably colored so that the surface of the wings will present a neat ornamental appearance. These wings will also have sufficient spring so that they may be separated to allow the insertion of a new abrading plate should such a substitution ever become necessary. Generally, however, the surfaces of the abrading plate will permanently be sufficiently abrasive to grind the pencil point to the desired taper, and renewal of the plate will be unnecessary.

The device may of course be made in any suitable size and in various ways the details of construction herein used and described may be modified and still be within the scope of my invention.

I claim as my invention:

A pencil sharpener including a substantially U-shaped integral holder comprising spaced apart side walls having a top wall connecting them together, a knife blade attached to the upper wall, a flexible guide tongue also on the upper wall having its free end extending in a direction towards the knife blade and bent downwardly and positioned adjacent to the cutting edge of said blade, the free end of said tongue lying substantially in the medial plane of the blade, said tongue being bendable whereby it may be adjusted

relatively to the knife edge to regulate the depth of the cut, and a thumb rest provided on said holder adjacent to said blade whereby the user may readily support the holder with the thumb while drawing a pencil through the sharpener to sharpen it.

In witness whereof, I have hereunto set my hand this 5th day of April, 1928.

NEAL G. BARNARD.
